CLAIM

The ornamental design for a locking apparatus for sliding windows and doors, as shown.

DESCRIPTION

FIG. 1 is a top plan view of a locking apparatus for sliding windows and doors, showing my new design;
FIG. 2 is a front elevational view thereof;
FIG. 3 is a bottom plan view thereof;
FIG. 4 is a right side elevational view thereof;
FIG. 5 is a rear elevational view thereof;
FIG. 6 is a left side elevational view thereof; and
FIG. 7 is a top perspective view thereof, with the broken-line showing of the portion of the window being for illustrative purposes only and forming no part of the claimed design.

FIG. 1

FIG. 4

FIG. 2

FIG. 5

FIG. 3

FIG. 6

FIG. 7
